UNITED STATES PATENT OFFICE.

EDWARD J. BROOKS, OF EAST ORANGE, NEW JERSEY, ASSIGNOR TO E. J. BROOKS & CO., OF NEW YORK, N. Y.

SEALING-PRESS.

SPECIFICATION forming part of Letters Patent No. 254,601, dated March 7, 1882.

Application filed October 31, 1881. (No model.)

To all whom it may concern:

Be it known that I, EDWARD J. BROOKS, a citizen of the United States, residing at East Orange, in the county of Essex and State of New Jersey, have invented a new and useful Improvement in Sealing-Presses, of which the following is a specification.

This invention relates to means for sealing and labeling railway freight-cars.

In lieu of or in addition to a small tag combined with or attached by the seal which secures the car-door—as shown and described, for example, in my drawings and specification forming part of Letters Patent No. 178,722, dated June 13, 1876, No. 209,008, dated October 15, 1878, No. 235,668, dated December 21, 1880, or No. 236,539, dated January 11, 1881—the officers of most roads prefer to use a relatively-large labeling-card, indicating by conspicuous characters the contents of the car, the point where it was loaded, its destination, the date on which it was sealed or shipped, &c., said card being attached to the door or side of the car by means of tacks; and heretofore the man who seals the cars has had to carry two distinct tools—namely, a sealing-press and a hammer—in order to press the seals and attach the cards.

The object of the present invention is to adapt one tool to do the whole of this work, so as to save the trouble, time, and labor involved in finding, using, and carrying about a second tool, as well as the cost of the latter, or a considerable part thereof; and this invention consists in a sealing-press with a hammer attachment, as hereinafter more fully set forth.

Figure 1 of the accompanying drawings is a perspective view of a sealing-press with hammer attachment and of a portion of the side of a sealed and labeled freight-car, showing the former as used in hammering on the labeling-card. Fig. 2 is an edge view of the sealing-press on a larger scale. Fig. 3 is a side view of the same, partly in longitudinal section on the line 3 3, Fig. 2; and Fig. 4 is a small side elevation of the press with dies separated, as in the act of receiving a seal to be pressed.

A, Fig. 1, represents the side of the car; B, the car-door; C, the labeling-card; and D, the pressed seal, the latter in the example being formed from one of my lead-and-tin seal-blanks

patented August 23, 1881, as described in my specification forming part of Letters Patent No. 246,068, with the disk alone pressed, as shown at Fig. 22 in my drawings forming part of Letters Patent No. 178,722, before mentioned. 55

The illustrative sealing-press (shown in perspective in Fig. 1 and in detail in Figs. 2, 4) is adapted, for example, to press lead-and-tin seals of the aforesaid description.

In practice presses for all the various forms 60 of seals in use which require pressing or punching in attaching them may be constructed according to this invention, and I propose so applying it; but for clearness the succeeding description will be confined to the press shown. 65

This sealing-press is composed of two malleable-iron castings, E F, a pair of steel dies, G H, and a steel spring, I, with a steel pivot-pin, p, and screws s s for uniting and securing the parts, the hammer attachment h being formed 70 on the main part E, so as to be integral therewith and most advantageously located. Said main part E forms at its larger and heavier end, on which the hammer attachment h is formed, what is termed the “head” of the 75 press, which is cored and drilled to receive, first, the bed-die G, with, its clamping-screw, then the upper die, H, and spring I, introduced together with the screw which attaches the latter between the cheeks of the head, and, finally, 80 the other main part, F, with the pivot-pin p, an open mouth of ample size being formed in said head between a pair of rigid jaws to receive the seal-disk preliminary to pressing it, as illustrated by Fig. 4, and to freely disengage the 85 pressed seal. The corresponding end of said part F is constructed with parallel sides, a drill-hole perpendicular thereto to receive the pivot-pin p, and an eccentric projection or cam, e, on its lower edge, to coact with the upper end of 90 the sliding die H for depressing the latter to compress and stamp the seal-disk, said die H being of the common cylindrical form, with a horizontal socket to receive the free end of the spring I, which operates as a lifting-spring, 95 tending to hold the part F and die H in elevated position, as shown in Fig. 4, the lower end of said die H being lettered and provided with a central sharp-pointed punch to puncture and interlock the sealing-disk and sheet-metal 100

strip of the seal D in the act of compressing and stamping the former upon the bed-die G, while this die G is simply supported solidly in line with said die H and constructed with a central depression matching said punch to receive the punch end and a portion of the soft metal displaced thereby at the pressing operation.

- 10 The hammer attachment h is formed in line with the dies G H in the form of the face end of a hammer-head, and serves to accommodate the lower end of the socket drilled to receive said dies while it is thus located on the solid edge of the press at its heavy end in line with 15 the greatest thickness of metal, and it may be with the latter practically solid in line therewith, the dies being adapted to come in contact with each other when there is no seal in the press, if so preferred.
- 20 The handle ends of the parts E F are constructed with reference to being grasped together in the right hand, as shown in Fig. 1, in carrying the tool and in using it to drive

the tacks or small nails used to attach the card C, as illustrated in said figure. After it 25 has been so used the lower handle is simply released by the fingers to bring the press to the condition illustrated by Fig. 4 preparatory to pressing the seal D.

I claim as new and desire to secure by Let- 30 ters Patent—

In a sealing-press composed principally of two main parts, E F, having lever-handles integral therewith, and a head on one of said parts containing a pair of seal-dies substantially at right angles to said handles, the combination, with said head, of a hammer attachment, h, formed on the lower edge of said head in line with said dies, substantially as herein specified, for the purpose set forth.

In testimony whereof I affix my signature in presence of two witnesses.

EDWARD J. BROOKS.
